UNITED STATES PATENT OFFICE.

GRACE T. HERRICK, OF PALO ALTO, CALIFORNIA.

DESIGN FOR AN IMAGE OR STATUETTE.

56,612.

Specification for Design.

Patented Nov. 16, 1920.

Application filed October 16, 1919. Serial No. 331,191. Term of patent 3½ years.

To all whom it may concern:

Be it known that I, GRACE T. HERRICK, a citizen of the United States, residing at Palo Alto, county of Santa Clara, State of California, have invented a new, original, and ornamental Design for an Image or Statuette, of which the following is a specification, reference being had to the accompanying drawings, forming a part thereof.

Fig. 2 is a front elevation of the same.

The image or statuette may be fantastically painted in variegated colors without materially departing from the scope and general appearance of the design.

I claim:—

The ornamental design for an image or statuette as shown.

GRACE T. HERRICK.
